(57) **CLAIM**

The ornamental design for a headband with light, as shown and described.

DESCRIPTION

FIG. 1 is a perspective view of a headband with light; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; and, FIG. 8 is a bottom plan view thereof. The broken lines in the drawings depict portions of the headband with light that form no part of the claimed design.
